US00D960832S

(12) **United States Design Patent** (10) **Patent No.:** **US D960,832 S**
Chang et al. (45) **Date of Patent:** **** Aug. 16, 2022**

(54) **POWER ADAPTER**

(71) Applicant: **SEA SONIC ELECTRONICS CO., LTD.**, Taipei (TW)

(72) Inventors: **Hsiu-Cheng Chang**, Taipei (TW); **Cheng-Yung Lo**, Taipei (TW)

(73) Assignee: **SEA SONIC ELECTRONICS CO., LTD.**, Taipei (TW)

(**) Term: **15 Years**

(21) Appl. No.: **29/735,335**

(22) Filed: **May 20, 2020**

(51) LOC (13) Cl. **13-02**

(52) U.S. Cl.

USPC **D13/110**; D13/123

(57) **CLAIM**

The ornamental design for the power adapter, as shown and described.

DESCRIPTION

FIG. 1 is a perspective view of the power adapter showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view;

FIG. 9 is an enlarged partial view thereof taken from the top of FIG. 2;

FIG. 10 is an enlarged partial view thereof taken from the bottom of FIG. 2;

FIG. 11 is an enlarged partial view thereof taken from the top of FIG. 3; and,

FIG. 12 is an enlarged partial view thereof taken from the bottom of FIG. 3.

The Dash-Dash broken line in the drawings illustrate features of the power adapter that form no part of the claimed design. The Dash-Dot-Dash broken line edge of the enlarged view and forms no part of the claimed design.

1 Claim, 8 Drawing Sheets
